UNITED STATES PATENT OFFICE.

LEVI J. LENNOX, OF DETROIT, MICHIGAN.

DESIGN FOR A HEATING-STOVE.

SPECIFICATION forming part of Design No. 26,368, dated December 1, 1896.

Application filed September 19, 1896. Serial No. 606,445. Term of patent 7 years.

To all whom it may concern:

Be it known that I, LEVI J. LENNOX, a citizen of the United States, residing at Detroit, county of Wayne, State of Michigan, have invented and produced a new and original Design for a Heating-Stove, of which the following is a specification, reference being had to the accompanying drawing, showing a part thereof.

10 The drawing is a view in perspective showing my design.

The leading features of my design consist in a base A, of circular outline, ornamented with scrollwork, mounted upon legs B, ornamented on their outer surfaces. Upon the base A rests a dome C, of open-work formed 15 by converging upwardly-extended bars c, in-

tersected by horizontal parallel bars c', the bars c being united by a circular rim c² at the bottom of the dome, the top c³ of the dome being flat. To the rear of the dome and rising from the base A is a shield-shaped back D, ornamented with scrollwork and having scallops at its edges.

What I claim as my invention is—

25 The design for the heating-stove herein shown and described.

In testimony whereof I sign this specification in the presence of two witnesses.

LEVI J. LENNOX.
